(57) **CLAIM**

The ornamental design for a stanchion handle, as shown and described.

DESCRIPTION

FIG. 1 is a top front perspective view of a stanchion handle; FIG. 2 is a bottom rear perspective view of a stanchion handle; FIG. 3 is a front view of a stanchion handle; FIG. 4 is a rear view of a stanchion handle; FIG. 5 is a top view of a stanchion handle; FIG. 6 is a bottom view of a stanchion handle; and, FIG. 7 is a side view of a stanchion handle.

The broken lines depict portions of the stanchion handle in which the design is embodied that are not considered part of the claimed design.
